ORE CONDITIONING DEVICE

Joseph P. Ruth, Jr., Denver, Colo.

Application February 6, 1933, Serial No. 655,390

2 Claims. (Cl. 259—7)

This invention relates to improvements in ore conditioning apparatus of the type employed in connection with froth flotation ore separation.

I have found that for the successful separation of certain kinds of ores, it is necessary to remove the soluble air and oxygen from the pulp prior to treatment by froth flotation and in order to enable me to successfully condition the ore in the absence of oxygen, I have found it necessary to devise a conditioning apparatus in which the ore pulp can be agitated for the required length of time in contact with certain inhibiting chemicals without introducing air and oxygen into the pulp.

15 This invention, briefly described, comprises a conditioning tank that is provided with an agitating propeller and whose top is closed in such a way that no air can enter, or liquid leave, except through an opening especially provided for this purpose. The pulp, which is mixed with deaerated water, is introduced to the conditioning tank underneath the top and the parts are so arranged that the liquid level forms a seal that prevents the introduction of air or oxygen 25 during the conditioning operation. The length of the conditioning operation is determined by the rate at which the pulp is permitted to flow into the conditioning tank.

Having thus briefly described the objects of 30 the invention and the apparatus by which the objects are attained, the apparatus will now be described in detail and for this purpose reference will be had to the accompanying drawing in which the preferred form of the apparatus has 35 been illustrated, and in which:

Fig. 1 is a vertical section through the conditioning tank; and

Fig. 2 is a view of the upper portion of the apparatus, looking in the direction of arrow 2, 40 Fig. 1.

The apparatus which forms the subject of this invention comprises a cylindrical tank 5 whose bottom has been indicated by reference numeral 6. This tank has been shown as supported on 45 a floor 7 resting on the joists 8. The top of the tank is closed by a cover 9, which, in the form illustrated, is somewhat frusto-conical in shape. Plate 9 is provided with a central opening 11 and extending downwardly from this opening is a pipe 12. Secured to the lower end of the pipe are spacers 13 to the lower ends of which the plate 14 is secured by being welded thereto. The plate 14 and pipe 13 are preferably supported by means of angularly related 50 brace rods 15, whose tension can be varied by

the turnbuckle 16. Extending into the opening 11 from above is a short pipe 17 and surrounding this pipe is a casting 18 having its bottom provided with an opening 19. The space between the pipe 17 and the side of the opening 19, is filled with some packing material which is held in place by a ring 20. Member 18 has an opening 21 on the side from which a pipe 22 extends. Any material that passes upwardly through the pipe 12 flows into the interior of member 18 and thence out through the pipe 22. Member 18 can be rotated about the pipe 17 so that pipe 22 can be adjusted to discharge from any side of the conditioning apparatus.

The cylindrical wall 5 is provided with an opening 23 and this is enclosed by the walls of a reception compartment 24. The upper edges of the walls of compartment 24 is provided with an outwardly extending flange 25 which cooperates with a similar flange 26 secured to a feed mechanism comprising a hopper whose bottom has been indicated by reference numeral 27. A brace 28 extends from the plate 29 near the upper and outer end of the bottom 27 to a corresponding plate 30 secured to the wall of compartment 24. The hopper has an end wall 31, two side walls 32 and an end wall 33. Journaled in the two side walls 32 are shafts 34 and 35. Secured to the shaft 34 is a sprocket wheel 36 and rotatably mounted on shaft 35 is a wheel 36'. A sprocket chain 37 encircles the wheels 36 and 36' and is provided with angular lugs 38 for a purpose which will hereafter appear. An electric motor 39 is connected by means of a belt 40 with a wheel 41. When the motor is 35 in operation the belt travels in the direction of the arrow. One side of the compartment 24 has an opening for the reception of one end of the pipe 59.

Extending above the top of the conditioning tank is a frame work comprising two vertical standards 42 which are held against sidewise motion by braces 43 as shown in Fig. 2 and are held against transverse motion by braces 44 as shown in Fig. 1. Diagonal braces 45 serve to increase 45 the rigidity of the structure. Secured to the upper ends of members 42 is a channel iron 46 and a similar channel iron 47 is secured to the uprights near the bottom as shown in Fig. 2. Secured to the web of channel iron 46 is a bearing 48 and a similar bearing 49 is secured to the web of channel iron 47. An impeller shaft 50 is mounted for rotation in bearings 48 and 49 and has secured to its lower end a propeller 51. The upper end of shaft 50 is provided with a grooved 55

belt pulley 52 with which the belts 53 cooperate. A motor 54 is supported on brackets 55 and when in operation rotates the propeller shaft 50.

When the machine is in operation pulp, which has preferably been filtered, is introduced into the hopper which contains the conveyor belt and is gradually fed into the receiving compartment 24. Daeaerated water is introduced through pipe 59 into the receiving compartment. The material 10 fills the interior of the conditioning tank to the level of the top of pipe 17 and as a result the liquid level in the receiving compartment is at the place indicated by dotted line 56. The pulp, the deaerated water, and the conditioning chemicals 15 are introduced into the conditioning tank and subjected to agitation by the propeller 51. The rate at which the material is introduced determines the rate at which it leaves and the time of treatment can therefore be regulated by regulating the feed. Instead of introducing the pulp 20 and the deaerated water separately as shown in the drawing, it is possible to introduce both the pulp, the water and the chemicals through pipe 59, in which case the feed hopper can be removed, 25 if desired, and the top of the receiving tank closed or the feed apparatus can simply remain as shown, but need not be operated.

It is evident that by means of the machine shown on the drawing and described herein, ore 30 can be agitated to any extent and for any time required, in the absence of air, and therefore in processes that require the pulp to be free from oxygen, this agitation can be carried on without danger of introducing oxygen which would interfere with the successful separation of the 35 minerals.

Although I have shown and described the specific apparatus by means of which conditioning 40 and agitation can be carried out free from air or oxygen, it is evident that machines differently constructed could be substituted for the one shown and the machine described and illustrated should therefore be considered merely as one embodiment 45 of means for the purpose under consideration.

45 In order to protect the bottom 16 from the excessive wear to which it would otherwise be

subjected, I have shown a protecting plate 57 which is supported on a board platform 58 that in turn is supported from the upper surface of bottom 6. The propeller is operated in such a way that the material is forced downwardly at the center as indicated by the arrows and it will therefore move downwardly towards the bottom and upwardly along the sides and finally pass out through the pipe 12.

Having described the invention what is claimed 10 as new is:

1. A device for conditioning and agitating deaerated ore pulp in the absence of air comprising, in combination, a closed tank, the top of the tank having a discharge opening, a pipe extending downwardly from the discharge opening to a point above the bottom of the tank, a baffle plate located below the lower end of the pipe and secured to the latter by spacers, the plate having an opening, a shaft extending through the discharge opening, the pipe and the opening in the plate, a propeller agitator secured to the lower end of the shaft, means for rotating the shaft and the agitator, the side of the tank having an inlet opening below the top, and means for introducing deaerated pulp into the tank through the inlet opening.

2. A device for conditioning and agitating ore pulp in the absence of air comprising, in combination, a closed tank, the top of the tank having a discharge opening, a pipe extending downwardly from the discharge opening to a point above the bottom of the tank, a baffle plate located below the lower end of the pipe and spaced from the latter, means for holding the plate in position, the plate having an opening, a shaft extending through the discharge opening, the pipe and the opening in the plate, a propeller agitator secured to the lower end of the shaft at a point below the plate, means for rotating the 40 shaft and the agitator, the side of the tank having an inlet opening below the top and means for introducing pulp into the tank through the inlet opening.
